COMBINED PLIERS AND SCREW DRIVER

Andrew G. Koon, Redlands, Calif.

Application July 16, 1935, Serial No. 31,667

1 Claim. (Cl. 81—5.1)

This invention relates to screw drivers and more particularly to a screw driver construction combined with a pair of pliers to permit the loosening of screws or bolts which are relatively hard to loosen or tighten.

An object of this invention is to provide a construction of this kind which is particularly adapted for use in tightening or loosening the bolts or screws used as pivots for shears or like instruments.

Another object of this invention is to provide an adjustable blade structure which is slidably mounted in one side of a plier construction in a position confronting the other side or jaw of the pliers.

The above and various other objects and advantages of this invention will in part be described in, and in part be understood from the following detail description of the present preferred embodiment, the same being illustrated in the accompanying drawing wherein:

Figure 1 is a detail side elevation of a device constructed according to an embodiment of this invention.

Figure 2 is a detail plan view of the device.

Figure 3 is a detail front elevation of the device in applied position on a pair of scissors shown in fragmentary form.

Figure 4 is an enlarged fragmentary side elevation partly in longitudinal section showing the device in operative position.

Referring to the drawing wherein like numerals of reference designate corresponding parts throughout the several views, the numerals 10 and 11 designate a pair of handles or levers which are mounted on a pivot 13. The handle or lever 10 has a jaw member 12 secured to the forward end thereof and the handle 11 has a second jaw member 14 secured to the forward end thereof and in confronting position to the first jaw member 12.

In order to provide a means whereby the plier construction including the handles 10 and 11 and the jaws 12 and 14 may be used to loosen or tighten screws, bolts or other like articles, I have provided a blade 15 having a stem 16 which is slidable through the jaw 12 adjacent the forward end of this jaw. The blade 15 is constructed after the manner of a screw driver blade and the inner side of the jaw 12 is provided with a pair of right angularly related recesses 17 in a selected one of which the inner end of the blade 15 is adapted to engage. The stem 16 is threaded, as at 18, and a nut 19 engages the threads 18 so as to limit the

sliding movement of the stem 16 through the jaw 12.

A spring 20 is secured, as by a bolt or screw 21, to the outer side of the jaw 12 and is provided with a slot 22 in its forward end which loosely engages about the stem 16. This spring 20 engages against the outer side of the nut 19 and acts to constantly urge the blade 15 inwardly so that the blade 15 may be turned to permit engagement of the outer end thereof in a selected recess 17.

In this manner, the jaws 12 may be pressed together by means of the handles 10 and 11 and the bolt 23 turned slightly and then the jaws 12 and 14 may be released to permit return of the clamping means to the original position with the blade 15 remaining stationary. It will be obvious that the device may be turned for a quarter turn each time or a greater turn if such is possible and the spring 20 will maintain the blade 15 in engagement with the kerf of the bolt 23.

This combined screw driver and pliers may, therefore, be used to loosen or tighten bolts or screws which are relatively hard to move, these bolts being of a type used for scissors or like instruments. The blade 15 by reason of the tight grip obtained through the jaws 12 and 14 will not break the kerf in the screw or bolt 23. Preferably, the jaw 14 on its inner side is provided with a concave recess 24 in which the end of the bolt 23 projecting through the blades of the scissors 25 may engage.

In the use and operation of this device, the nut 19 is suitably adjusted so that the spring 20 will normally maintain the outer end of the blade 15 out of engagement with the right angularly related recesses 17 which form the locking means to hold the blade 15 against turning. The blade 15 is then engaged with the kerf of the bolt 23 and then the handles 10 and 11 swung one toward another so that the outer end of the blade 15 will engage in a selected recess or locking means 17. The entire handle structure is then turned for a fragment of a turn with the blade 15 and the stem thereof as a fulcrum. When the handle structure is turned for a fragment of a turn, the handles 10 and 11 may be released slightly so as to permit the spring 20 to move the blade 15 out of the previously engaged recess 17. The handles 10 and 11 may then be swung to their original position with the blade 15 remaining stationary. The bolt 23 may thus be either tightened or loosened, as may be desired, and a considerable degree of pressure may be applied to the blade 15 so that this blade will not slip out of the kerf 55

of the bolt 23 and the bolt 23 may be tightened or loosened as may be desired.

I claim:—

5 A device as set forth, comprising a pair of jaws, a pair of pivoted handles secured to the jaws, a flat screw driver blade between the jaws, a reduced round stem secured to the blade, one of said jaws having an opening transversely therethrough in which said stem is slidably and rotatably mounted, said stem having a threaded outer end portion, a nut threaded on to the stem for limiting the inward movement of the blade, a 10 spring having a stem receiving slot engaging the

nut to constantly urge the blade inwardly, said one jaw having a recess in the inner face thereof to receive an end of the blade for holding the blade against rotation and said spring normally urging said blade out of said recess and said one jaw having a recess on the face opposite from said first face in which said nut engages, said latter recess being of a depth substantially equal to the thickness of the nut whereby said spring will hold the nut in said latter recess when the 10 blade is in released position.
